[57] CLAIM

The ornamental design for a tooth mirror, substantially as shown and described.

DESCRIPTION

FIG. 1 is a perspective view of a tooth mirror embodying my new design;

FIG. 2 is a front elevational view thereof;

FIG. 3 is a right side elevational view thereof, the left side elevational view being a mirror image of said right side elevational view;

FIG. 4 is a rear elevational view thereof;

FIG. 5 is a top plan view thereof;

FIG. 6 is a bottom plan view thereof; and

FIG. 7 is a perspective view thereof, in the open position.

FIG. 1

FIG. 2

FIG. 3

FIG. 4

FIG. 5

FIG. 6
